[57] CLAIM

The ornamental design for an combined lamp and transformer housing for track light, as shown and described.

DESCRIPTION

FIG. 1 is a front, left side and upper perspective view of an combined lamp and transformer housing for track light showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The yoke, track mount and portion of the track are shown in broken lines for illustrative purposes only.

FIG. 2.

FIG. 3.
